CHARLES RADIGUER, OF ST.-DENIS, FRANCE, ASSIGNOR TO THE SOCIETE ANONYME DES ETABLISSEMENTS DELAUNAY-BELLEVILLE, OF ST.-DENIS, FRANCE, A CORPORATION OF FRANCE.

LIQUID-FUEL ATOMIZER.

1,168,416.

Specification of Letters Patent. Patented Jan. 18, 1916.

Application filed June 18, 1914. Serial No. 845,877.

To all whom it may concern:

Be it known that I, CHARLES RADIGUER, citizen of the French Republic, residing at St. Denis, Department of the Seine, in France, have invented certain new and useful Improvements in or Relating to Liquid-Fuel Atomizers; and I do hereby declare the following to be a full, clear, and exact description of the invention, such as will enable others skilled in the art to which it appertains to make and use the same.

Mechanical atomizers of liquid are known which operate as follows: Before leaving the apparatus, the liquid traverses a first series of orifices suitably arranged which may be called the preliminary orifices, and which impart to it a rotatory speed about an axis; it follows that the molecules of the liquid travel in the atomizer describing around its axis helices having a short pitch; they thus reach the outlet or final orifice. When traversing the latter they acquire under the action of pressure a speed of translation parallel to the axis. At every point of the outlet orifice, the tangential speed of the movement of rotation and the speed of translation combine and each molecule describes an oblique trajectory on the axis of the atomizer; all the molecules together constitute a conical surface which forms a sheet of atomized liquid. The angle of this conical surface depends upon the relative magnitude of the speed of rotation and of the speed of translation. In these apparatus the output of the atomizer is varied by varying either the number or the section of the preliminary orifices which impart rotatory speed, or the section of the final orifice which imparts a speed of translation. These two methods according to which only one of the speeds is acted upon, are defective because they do not enable to maintain a constant relation between the speeds. The angle of the cone of atomization therefore varies considerably. According to the invention, this drawback is eliminated by providing a controlling member which acts simultaneously on the section of the preliminary orifices and on that of the final orifice; whatever the position of this member may be, that is to say, whatever the output, the two outlet sections remain in a relation substantially constant and the angle of the cone

of atomization also remains substantially constant. These arrangements are illustrated in the accompanying drawing, in which,

Figure 1 is a section on line X—X of Fig. 2. Fig. 2 is a plan. Fig. 3 is a section on line Y—Y of Fig. 1. Fig. 4 is a section on line Z—Z of Fig. 1.

The cylindrical body 1 of the apparatus is mounted on the face plate of the boiler; it is secured thereto by means of its flange 2 (Fig. 3). Within the body 1 there is a hollow cylinder 3 provided with a fluid-tight packing 4; in the interior the cylinder 3 is formed with longitudinal orifices 5, 5, around which a metal sleeve 6 is mounted, constituting a filter.

On the right of Fig. 1, a short hollow cylinder 7 is screwed on the end of the cylinder 3, said short cylinder extending to, and bearing against the screw-threaded plug 8 which is formed at the center with the atomizing orifice 9. A rod 10 with its packing 11 engages within the cylindrical member 3, its part 12 screwing therein. The end portion 13 of the rod 10 screws into a solid cylinder 14 the end of which is conical parallelly to the plug 8; the member 14 slides freely in the cylinder 7, but a set screw 15 which it carries and which engages a longitudinal notch of the cylinder 7 prevents it from rotating. The displacement of this member 14 controls the output. On the left, the distance piece 16 carries securely a socket 17 which is traversed by the rod 10, a pin 18 the end of which is engaged in a groove formed on the said rod 10, is movable within a notch 19 formed in the said socket when the former moves forward or backward. A dog integral with the said pin engages a slot formed in the pointer 20 and the displacements of the latter on the dial 21 indicate the various degrees of opening of the atomizer. In Fig. 1, the atomizer is shown fully opened.

The liquid fuel is supplied under pressure through the elbow-shaped pipe 22 and spreads out in the space 23 around the filter 6 which it traverses; it passes through the openings 5, enters the body of the cylinder 3, leaves through the openings 24 formed in the cylinder 7 and fills the capacity 25 around the member 7; thence the liquid fuel

passes, always under pressure, through the oblique openings 26, Fig. 4 formed at the end of the cylinder 7 which impart to the fuel a rotatory movement; the fuel fills, 5 always rotating, the capacity 27 and finally leaves through the orifice 9 which imparts to it a movement of translation along the axis. From the combination of these two movements an atomization results, along the 10 external surface of a cone the apex of which is at 9 and the axis of which is that of the atomizer.

By moving the regulator 14 away from the plug 8, the passage of the fuel through 15 the central opening 9, which controls the output along the axis is increased; it controls at the same time the circumferential output by opening a greater surface of the oblique openings 26. This arrangement enables these two outputs to be always maintained in an approximately constant relationship. The screws 12 and 13 are threaded in the same direction, but of different pitch; that of the screw 13 being smaller. It follows therefrom that for one revolution of 25 the controlling wheel, the screw 10 pulls or pushes the regulator 14 through a distance equal to the difference in pitches. It is thus possible to obtain very slight variations in 30 the openings without shock.

I claim:

1. In a liquid fuel burner, a cylindrical sleeve provided with at least one tangential opening, a plug having a conical inner surface and a slidable regulator mounted in 35 said sleeve to control said opening and having a conical surface parallel to the conical surface of the plug to form a whirl chamber into which said tangential opening discharges, and means to actuate said regulator 40 to control the output of the burner.

2. The combination with a fuel burner, of a rotatable and longitudinally movable rod capable of controlling the discharge of fuel from the burner, a stationary sleeve in which 45 said rod moves, a pointer pivoted on said sleeve, a pin carried by the pointer, said sleeve having an opening through which the pin projects toward the rod, said rod having a recess in which said pin engages so that 50 longitudinal movement of the rod shifts the pointer, and a stationary index with which said pointer coöperates.

In testimony whereof I affix my signature, in presence of two witnesses.

CHARLES RADIGUER.
